UNITED STATES PATENT OFFICE.

GEORGE ROUSSEL, OF DONNER, LOUISIANA.

MEANS FOR SECURING RAILS IN PLACE.

1,407,677.

Specification of Letters Patent. Patented Feb. 21, 1922.

Application filed September 9, 1921. Serial No. 499,374.

To all whom it may concern:

Be it known that I, GEORGE ROUSSEL, a citizen of the United States, residing at Donner, in the parish of Terrebonne and 5 State of Louisiana, have invented certain new and useful Improvements in Means for Securing Rails in Place; and I do hereby declare the following to be a full, clear, and exact description of the invention, such as 10 will enable others skilled in the art to which its appertains to make and use the same.

My invention relates to improvements in means for securing rails to wooden cross ties.

15 The usual practice is to drive the spike into the tie at each side of the rail and have one side of the head of the spike engage the flange of the rail, but owing to the heavy pressure that is brought on the rails there 20 is a tendency of the rails to spring upwards after the wheels of the train pass over the roadbed, with the result that the spikes gradually become loose and accidents are liable to occur. Moreover it is necessary to 25 constantly inspect the roadbed to provide against accidents due to loose spikes.

According to my invention I provide an arrangement by which it is impossible for the spikes to pull out of the cross tie incident to the normal operation of the road.

30 My invention comprises the combination with the rail of a rail plate supporting the same, spikes driven through openings left in said rail plate and provided with shoulders, and wedges holding said shoulders in 35 engagement with the wedge plate, with means for locking these wedges against accidental removal.

My invention will be more fully understood after reference to the accompanying drawings, in which like parts are indicated by corresponding symbols throughout the several views, and in which:—

Figure 1 shows a cross section through 45 the rail and rail plate, with one of the spikes and wedges shown in section, and the other in elevation, and with part of the wooden cross tie shown in section, the parts being in the assembled position.

50 Figure 2 is a similar view to Fig. 1, but shows one of the spikes after it has been driven down in the tie, and just as the wedge is about to be inserted.

Figure 3 is an elevation of the spike showing the flat back thereof.

Figure 4 is an elevation of the spike from

the front and showing the engaging shoulder; and

Figure 5 is a rear view of the wedge. A represents the wooden cross tie; B the rail plate which is provided with perforations *b* of somewhat greater diameter at right angles to the rail than is the maximum thickness of the body of the spike, as shown most clearly in Fig. 2.

65 C represents the rail which may be of the usual or any desired construction, provided with the usual flanges *c*, which rail rests upon the rail plate B.

D represents a spike constructed according to my invention, which spike is provided with the usual pointed tip *d* to be conveniently driven into the wood. The back of said spike is preferably flat as at *d'*, and at the upper end it is provided with a head 70 *d*² projecting inwards towards the rail and inclined upwards slightly on its lower face, as at *d*³. Below this inclined face *d*³ is a transverse channel *d*⁴ in the spike, the lower 75 edge of which is rounded by the shoulder *d*⁵ above the wedge face portion *d*⁶ on the front of the spike. By the front of the spike I mean the side next the rail, and by the back of the spike I mean the side away from the rail.

80 In the back of the head of the spike I provide a recess *d*⁷ to engage the inner end *f*² of the locking screw F, as will be herein-after more fully described.

85 Back of the spike, when in the assembled relation shown in Fig. 1, there is a wedge E which has the lower driving edge *e* and the head *e'*, which is provided with a projecting boss *e*² to carry the internal screw threads *e*³ surrounding the opening *e*⁰. The 90 head of the wedge may be provided with shoulders *e*⁴ if desired.

95 The screw threads *f* of the screw F engage in these screw threads *e*³ and this screw is provided with a head *f*' and with a point 100 *f*² which projects into the recess *d*⁷ in the spike, when the parts are in the assembled position, as already described.

105 In order to assemble the parts the plate B is mounted in place on the cross tie A with the inner wall *b*' of its opening *b* in the same plane with the outer edge of the flange *c* of the rail, as shown in Fig. 2, the spike is now driven down in place so that the shoulder *d*⁵ is just below the lower ends 110 of the plate B, the plate then being in the position shown in Fig. 2. Then the wedge

E is driven down from the position shown in Fig. 2 to that shown in Fig. 1, and finally the locking screw F is screwed in until its point f^2 projects into the recess d^7 . At 5 this time the parts are in the position shown to the left of Fig. 1, and it will be seen that the shoulder d^5 of the spike will engage below the plate B and will lock the spike against removal, while the screw bolt 10 F will lock the wedge E against slipping up on the spike and allowing the spike to yield in the backward direction.

Thus it will be seen that I provide an absolutely positive and safe lock for each 15 spike which will securely hold the spike against being raised out of the tie in the ordinary usage to which such devices are applied.

In order to remove the spike, unscrew the 20 bolt F, slide out the wedge E with any tool, such as a crowbar, engaging beneath the shoulders e^4 , then press the head of the spike backwards to clear the shoulder d^5 from the bottom edge of the plate B, and when the 25 spike is in the position shown in Fig. 2 it may be readily removed.

It will be obvious that various modifications might be made in the particular shape and arrangement of the several parts which 30 could be used without departing from the spirit of my invention; and I do not mean to limit the invention to such details except as particularly pointed out in the claims.

Having thus described my invention what 35 I claim and desire to secure by Letters Patent of the United States is:—

1. In a rail fastening arrangement, the combination with a flanged rail and a rail plate mounted above a cross tie and supporting 40 the rail, said rail plate being provided with a laterally elongated opening, of a spike having its body portion of somewhat less diameter than said opening and provided with a laterally projecting head, a 45 channel beneath the head, with a shoulder below said channel, the width of said channel being sufficient to engage the adjacent walls of the rail and of the opening, a wedge driven into said opening in rear of said spike, filling said opening and causing said shoulder to project beneath the bottom of said plate, and means for locking said wedge against withdrawal relative to said spike.

2. In a rail fastening arrangement, the

combination with a flanged rail and a rail 55 plate mounted above a cross tie and supporting the rail, said rail plate being provided with a laterally elongated opening, of a spike having its body portion of somewhat less diameter than said opening and provided 60 with a laterally projecting head, a channel beneath the head, with a shoulder below said channel, the width of said channel being sufficient to engage the adjacent walls of the rail and of the opening, a wedge 65 driven into said opening in rear of said spike, filling said opening and causing said shoulder to project beneath the bottom of said plate, and a set screw passing through said wedge and engaging a recess in said 70 spike.

3. A rail fastening arrangement comprising a rail plate adapted to be mounted above a cross tie and to support a rail, said rail plate being provided with a laterally elongated opening, a spike having its body portion of somewhat less diameter than said opening and provided with a laterally projecting head, a channel beneath the head, with a shoulder below said channel, the 80 width of said channel being sufficient to engage the adjacent walls of the rail and of the opening in the plate when the parts are assembled, a wedge adapted to be driven into said opening in rear of said spike and to cause said shoulder to project beneath the bottom of said plate, and means for locking said wedge against withdrawal relative to said spike.

4. A rail fastening arrangement comprising a rail plate adapted to be mounted above a cross tie and to support a rail, said rail plate being provided with a laterally elongated opening, a spike having its body portion of somewhat less diameter than said opening and provided with a laterally projecting head, a channel beneath the head, with a shoulder below said channel, the width of said channel being sufficient to engage the adjacent walls of the rail and of the opening in the plate when the parts are assembled, a wedge adapted to be driven into said opening in rear of said spike and to cause said shoulder to project beneath the bottom of said plate, and a set screw passing through said wedge and engaging a recess in 90 said spike.

GEORGE ROUSSEL.
